No. 12,356

July 12, 1881

UNITED STATES PATENT OFFICE.

GEORGE H. HUGHES, OF NEW YORK, N. Y.

DESIGN FOR ENAMELED AND TABLE OIL-CLOTH.

SPECIFICATION forming part of Design No. 12,356, dated July 12, 1881.

Application filed May 25, 1881. Term of patent 3½ years.

To all whom it may concern:

Be it known that I, G. H. HUGHES, a citizen of the United States, residing in the city of New York State of New York, have invented a certain new and useful Design for Enameled and Table Oil-Cloth, fully described and represented in the following specification and the accompanying fac-simile, forming a part of the same.

The design illustrated consists in a combination of six-pointed stars with ornamental stripes, the latter being twelve in number around each star, and radiating obliquely from it in pairs parallel with the right-hand side of each point. Each star-point embraces an angle of sixty degrees, and the stripe upon its right-hand side extends to the left-hand side of the star-point nearest to it, the latter star being viewed from the center of the first. The adjacent star-points are, therefore, separated by the width of the stripe, viewed at an angle of thirty degrees with its side. The stripe upon the left-hand side of each star-point extends parallel with the one upon the right side to a point centrally situated between three stars, the centers of the latter being equidistant from one another throughout the whole design. The figures are shown in the fac-simile as white upon a black ground, each star being defined by a narrow white border having a black line at each side of it. The body of the star exhibits a nearly white stippled surface, and a rosette, formed of six clover-leaves, of a darker stippled surface, fills the center of the

star and covers nearly one-half its area. The stripes are ornamented by an imitation of wood-graining, the longer stripes with a dark pattern and the shorter stripes with a lighter pattern of different character.

The essential features of the design are the stars containing the hexafoil rosettes, and the grained stripes radiating obliquely from the sides of the stars, as described, and I do not, therefore, limit myself to the precise details of ornamentation nor to the colors in which the design is illustrated, as it is the shape of the figures, and not their color, which constitutes my design.

The design may therefore be formed with any color upon a ground of contrasting hue, or it may be composed of several harmonious colors.

The design may be used to cover the entire surface of the enameled cloth, or for its middle, in combination with a suitable border, or otherwise employed upon the class of goods prescribed.

I therefore claim—

The design for table and enameled oil-cloth, substantially as herein shown and described.

In testimony whereof I have hereunto set my hand in the presence of two subscribing witnesses.

GEORGE H. HUGHES.

Witnesses:

HENRY G. GURNEY,
J. HAGUE ARMITAGE.
